US00D974336S

(12) **United States Design Patent** (10) **Patent No.:** **US D974,336 S**
(45) **Date of Patent:** **** Jan. 3, 2023**

(54) **MICROPHONE**

(71) Applicant: **ENPING CITY XUANYIN ELECTRONIC TECHNOLOGY CO., LTD**, Enping (CN)

(72) Inventor: **Guangye Lai**, Enping (CN)

(73) Assignee: **ENPING CITY XUANYIN ELECTRONIC TECHNOLOGY CO., LTD**, Enping (CN)

(**) Term: **15 Years**

(21) Appl. No.: **29/779,054**

(22) Filed: **Apr. 16, 2021**

(30) **Foreign Application Priority Data**

Mar. 4, 2021 (CN) 202130118770.7

(51) **LOC (14) Cl.** **14-01**

(52) **U.S. Cl.**

USPC **D14/225**

(57) **CLAIM**

The ornamental design for a microphone, as shown and described.

DESCRIPTION

FIG. 1 is a front and top perspective view of a microphone, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof; and,

FIG. 7 is a top plan view thereof.

The dashed broken lines in the figures illustrate portions of the microphone that form no part of the claimed design.

1 Claim, 7 Drawing Sheets
